UNITED STATES PATENT OFFICE

2,006,816

PROCESS OF PURIFYING AND DEWAXING
MINERAL OIL

George J. Strezynski, Poughkeepsie, N. Y., and
Walter Kronasser, Graz, Austria, assignors to
The De Laval Separator Company, New York,
N. Y., a corporation of New Jersey

Application October 23, 1933, Serial No. 694,760

4 Claims. (Cl. 196—18)

One of the steps in the production of high grade lubricating oils is treatment with concentrated sulfuric acid to remove undesirable constituents which, if left, cause dark color in the oil and are liable to break down in use.

In order to reduce darkening of the color of the oils this treatment is sometimes carried on at such low temperatures that solid waxes are thrown out of solution.

10 One of the methods for removal from the oil of the sludges formed by acid treatment is by centrifuging.

When this method is used on oils containing wax it is difficult and often impossible to obtain 15 continuous discharge of the sludge because of separation of wax in an independent layer between the sludge and the oil, resulting in plugging of the bowl.

One object of our invention is to provide a 20 process by which such treatment and separation can be accomplished without plugging.

Another step in the refinement of many oils is the removal of waxes that make the oils viscous or even solid at the temperatures at which 25 it is desired to use them.

The most used methods for removal of wax are chilling to throw the wax out of solution and gravity settling or centrifugal separation of the wax from the oil.

30 In all previously known methods it has been necessary to greatly dilute the oil and to chill it very slowly with slow agitation in order to produce wax particles that are large enough to be moved by gravity or centrifugal force. If the oil is chilled quickly, or is chilled at high viscosity 35 (without dilution) or is agitated while chilling, the wax will separate in particles too small for separation by any previously known methods.

We have discovered that it is possible to treat 40 mineral oil containing wax as to effect, by one series of operations, both de-waxing and acid purification. Our process comprises, in its preferred embodiment, the following series of steps. The oil, which may be a lubricating oil (either a 45 distillate or a residuum) or a crude oil, without substantial dilution or reduction of viscosity, is rapidly chilled with violent agitation. To the chilled oil is then added naphtha or some other diluent which it is known to add to oil to change 50 its viscosity and cause the oil and wax to have substantially different specific gravities and allow the particles to move freely through the liquid, such diluent having been previously chilled to a temperature not substantially above, and prefer- 55 ably substantially below, the temperature of the

previously chilled oil. With the diluted chilled oil is then mixed an acid, such as concentrated sulfuric acid. The acid may be, however, less preferably, added before, or at the same time that, the diluent is added. The mixed oil and diluent, or the mixed oil, acid and diluent, may or may not be still further chilled. The mixture is then subjected to centrifugal force and the acid-formed sludge and wax thereby separated from the oil, which is substantially wax-free.

In the above process, rapid chilling of the oil at high viscosity with agitation will not cause the wax to separate in particles too small for separation in the final step. On the contrary, the particles of sludge contact with the smaller wax 15 particles and, when separated out by centrifugal force or even by gravity, carry the wax particles along into the same mass as the sludge. Apparently the small particles of wax act as nuclei about which the sludge gathers, forming larger 20 particles, each of which behave as a unit in the centrifuge, so that, as above stated, the wax and sludge are thrown out as one mass. It is possible, but not advisable, to carry on the process by adding a small part of the diluent before the first 25 described chilling, but the degree of dilution must not approximate that effected at a later stage of the process. By having the diluent colder than the chilled wax-bearing oil, the rise in temperature due to the acid reaction may be counteracted, the latter action also being counteracted by further cooling the diluted oil prior to centrifugal separation. As the reaction between acid and oil constituents is very slow at extremely 30 low temperatures, it is sometimes advisable to only partially chill the oil before the acid treatment and finish the chilling to the temperature needed to obtain the desired cold test of the oil 35 after the acid has completed its action.

Whether the oil is subjected to one or a plurality of chilling operations, the temperature to which it should be chilled before centrifuging should be comparatively low, namely, varying 40 from 45° F. to substantially below 0° F., dependent 45 on the character of the oil and also on the cold test desired. In the case of some exceptional oils, the minimum temperature required for both purification and dewaxing may be as high as 45° F. When the oil is chilled in stages, with acid 50 treatment following the first chilling stage and centrifugal separation following the last chilling, the initial chilling need not be below 45° F., but may be lower, while the temperature of the last chilling may not be below 35° F. in the case of 55

exceptional oils, but will ordinarily be below 10° F.

The drawing is a diagram of a dewaxing plant adapted to practice my improved process.

5 From a tank 10, containing waxy oil, the oil flows into a tank 11 containing an agitator driven by a motor 12 and surrounded by a jacket 13 chilled by cold brine or other refrigerating fluid from a pipe 14. From a tank 15 a diluent flows 10 through a coil within a tank 16, in which the diluent is chilled to a temperature not substantially above, and preferably to a temperature somewhat below, the temperature of the oil and wax flowing from the chilling and agitating tank 11. The chilled and agitated oil and wax and the chilled diluent flow into a mixing and reaction tank 18, into which also flows mineral acid from a tank 17. The mixture of oil, wax, diluent and acid in tank 18 may be further chilled 15 by means of a coil 19 through which flows cold brine or other refrigerating fluid. From tank 18 the chilled mixture flows into a centrifuge 20, wherein the oil together with the diluent, or most of it, is separated from the acid sludge and 20 wax and any diluent which is not carried off with the oil.

What we claim and desire to protect by Letters Patent is:

30 1. In the process of dewaxing mineral oil by chilling, addition of a diluent and a mineral acid, and centrifugal separation of the oil from the acid-formed sludge, the preliminary step of chilling the oil with violent agitation before addition of the major part of the diluent, whereby the

wax is conditioned to so coalesce with the sludge so as to facilitate its separation from the oil.

2. In the process of treating mineral oil containing wax to purify it and remove wax therefrom, rapidly chilling the oil with violent agitation, chilling a diluent to a temperature not substantially above that of the chilled oil and adding the chilled diluent and a mineral acid to, and mixing them with, the chilled oil and wax, and separating the acid-formed sludge and wax from the oil.

3. The process of treating wax-bearing mineral oil to purify it and remove wax therefrom which comprises subjecting the oil to rapid chilling without substantial dilution to reduce its viscosity and to vigorous agitation, then adding a diluent adapted to reduce the viscosity of the oil and at a temperature not substantially above that of the chilled oil and also mixing with the chilled oil a mineral acid, chilling the diluted oil and acid-treated oil to further reduce its temperature, and separating the acid-formed sludge and wax from the oil.

4. In the process of treating mineral oil containing wax to purify it and remove wax therefrom, rapidly chilling the oil with violent agitation, chilling a diluent to a temperature below that of the chilled and agitated oil and wax and adding the chilled diluent and a mineral acid to, and mixing them with the chilled and agitated oil and wax, and separating the acid-formed sludge and wax from the oil.

GEORGE J. STREZYNSKI.
WALTER KRONASSER.
